To all whom it may concern:

Be it known that I, Emlin Cunningham, a citizen of the United States, residing at West Collingswood, in the county of Camden and State of New Jersey, have invented a new, original, and ornamental Design for a Bubble Canopy for Lamp Shades or the like, of which the following is a specification, reference being had to the accompanying drawing, forming a part hereof, in which:

Fig. 1 is a top perspective view of a bubble canopy for lamp shades showing my new design, the broken lines indicating a lamp being for illustrative purposes only;

Fig. 2 is a top plan view thereof;

Fig. 3 is a bottom plan view; and

Fig. 4 is an elevational view.

I claim:

The ornamental design for a bubble canopy for lamp shades or the like, as shown and described.
